CLAIM

The ornamental design for a tool storage rack as shown and described.

DESCRIPTION

FIG. 1 is a perspective view of a tool storage rack showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is an enlarged view of portion of FIG. 1; and,

FIG. 10 is an enlarged view of portion of FIG. 2.

The broken lines in the figures illustrate portions of the tool storage rack that form no part of the claimed design. The dot-dash broken lines represent boundaries of the enlarged portions and form no part of the claimed design.
